UNITED STATES PATENT OFFICE.

HENRY E. VEIT, OF CHICAGO, ILLINOIS.

BINDER FOR SHEET-MUSIC, &c.

SPECIFICATION forming part of Letters Patent No. 606,434, dated June 28, 1898.

Application filed October 29, 1897. Serial No. 656,759. (No model.)

To all whom it may concern:

Be it known that I, HENRY E. VEIT, a citizen of the United States, residing at Chicago, in the county of Cook and State of Illinois, 5 have invented a new and useful Improvement in Binders for Sheet-Music, &c., of which the following is a specification.

My invention relates to an improvement in binders for sheet-music and the like, my object being to provide, first, an improved covering in book form adjustable in thickness to the book contents and so arranged that the book contents will always open flat and remain open unweighted, and, second, to provide improved means for attaching the leaves together and to the cover.

A further object is to adapt a binding of this nature to the use of a scrap-book wherein provision is made for the ready insertion of 20 a varied collection of cards, letters, pictures, &c., requiring different modes of fastening.

To these ends my invention consists in the improved cover hereinbelow described, and, further, in the improved device for fastening 25 the leaves of sheet-music or the like together and which may be used either alone or in connection with said cover or some other suitable cover.

My invention is illustrated in the accompanying drawings, in which—

Figure 1 is a broken transverse section through the cover-sections of my improved binder, taken on line 1 of Fig. 2 and showing one of the separable binding-strips to which 35 the leaves are to be directly attached. Fig. 2 is a broken view, in plan perspective, of the cover-sections loosely fastened together and with one of the separable binding-strips in place. Fig. 3 is a broken view of an unfinished separable strip, showing the construction of the same; and Fig. 4 is an end view of 40 one of the separable strips, showing the manner of attaching leaves or the like.

The cover A is composed of two separable 45 sections B and C. The peculiar construction of these sections is among the important features of my invention, though I claim, broadly, a binder of this description having one of its sections provided at the rear edge with a slit 50 or pocket and the other provided throughout the length of its rear edge with a flexible tongue which slides within said pocket, thus

affording a back adjustable to the bulk of the book contents.

The cover-section B is provided with an inner sheet of cardboard *t*, to the rear edge of which is attached a securing-strip *D*, which extends substantially the length of the cover-section. The strip *D* comprises, preferably, 55 two narrow strips of thin cardboard *s*, pasted close together upon a strip of flexible material *r*, preferably of strong linen, said linen strip being of sufficient width to lap a great deal beyond the cardboard strips when folded to bring the cardboard strips together, as 60 shown in Fig. 1. This affords projecting strips *r'*, which are pasted upon the outer and inner surfaces of the rear edge of the inner sheet of cardboard *t*, as shown. The linen strip is pasted upon itself at the space between the strips *s* and the cardboard sheet *t* 65 to afford a hinge portion *r*². The strip is supplied toward both ends with two perforations *r*³ and *r*⁴. The section C is provided similarly with an inner sheet of cardboard *t* and 70 securing-strip *D*. In the case of this last-mentioned strip the inner perforations *r*⁴ are moved closer to the center and are supplied with headed binding-posts or fasteners *q*, 75 preferably paper-fasteners, as shown, which 80 are secured in place by inserting them through one thickness of the cardboard and linen and then bending the prongs before the linen strip is folded over to bring the two strips of cardboard into their superimposed 85 position. These binding-posts are allowed to project a short distance to receive the securing-cords *p*. The cover-section B is further provided with an outer sheet of cardboard *n*, to which is pasted the leather or 90 other binding material *n'* used, the latter being allowed to project a sufficient distance beyond the rear edge of the cover-section to afford a flexible back *E*. To the inner surface of the rear edge of the sheet *n* and to the 95 flexible back *E* is pasted a sheet of linen *m*, which serves as a reinforcing-strip. The edges of the binding-leather are folded over the edges of the sheets of cardboard in the usual manner and pasted on the inner surface of the sheet *t*, and the whole is then lined with a sheet of suitably-embellished paper *l*, 100 which is pasted upon the inner surface of the sheet *t* and overlapping the infolded edges of

- the binding-leather n' at the top and bottom, all in a usual manner. The make-up of the outer part of the section C is similar, except as it is varied by the formation of a pocket k between the strips t and n . Here the strip of linen m is dispensed with, while the leather binding extends only far enough beyond the rear edge of the sheet n as to allow it to be folded over the edge and pasted to the sheet 5 within the pocket. It is obvious that the pocket is closed at the upper and lower ends of the section by the folding of the binding-leather over upon the inner surface of the cover-section and pasting it there, as above 10 described. The depth of the pocket may be as great as desired, and I prefer to limit its depth by cementing the sheets of cardboard together over a margin of a couple of inches 15 at the outer edge of the cover-section.
- 20 The manner of securing the sections together is shown clearly in Fig. 2. The binding-cords p are knotted at one end and threaded through the holes r^3 r^4 of the section B, thence through the separable binding-strips, 25 thence through the holes r^4 of the section C, and finally are secured by winding their free ends about the binding-posts q and then tying them together.

There remains to be described a separable 30 binding-strip F, which, while it is peculiarly adapted to use with my improved cover, is also a valuable device when used alone or in conjunction with other covers. It comprises, preferably, a perforated cord-receiving securing-strip h and a plurality of gummed attaching-strips g g' g'' , &c. The strip h is made up of a strip of heavy tough paper h' , covered with strong linen h^2 . To one edge of this combined strip is cemented a strip of cardboard h^3 . The strip h and the plurality of strips mentioned are secured together along their longitudinal center line by linen or wire stitching h^4 before the strip h is folded back and pasted upon the cardboard strip h^3 . 35 Before the strips g g' , &c., are put together each is provided with a gummed surface, and the preferred manner of arranging the strips is to place the gummed surfaces together. When there is an odd number of strips, as 40 here shown, the folding of the inner one upon itself produces two adjacent gummed surfaces. The purpose of this arrangement is to provide for fastening in a double sheet f , as well as single sheets f' , it being immaterial 45 in the latter case on which side of the sheet the strip is pasted. Also when a thick sheet of material--such as a picture, a card, or the like--is to be inserted, often it is desirable to cement a strip upon each side of it, which is 50 permitted by the arrangement here shown.

In arranging sheet-music often it is desirable to use one of these separable strips or holders by itself. For instance, where it is desired to put the music into form for easy 65 carrying one of these strips may be used with or without the use of a flexible cover, and

this leaves the music in shape to be rolled up, so that it may be carried in the pocket.

In the use of the combined separable strips and the cover-sections provided with an extensible back the book always opens so that the pages lie flat, the peculiar construction of the separable strips, as well as the adjustment of the extensible back, contributing to the result. 75

The cover as I have described it is attractive in appearance, durable, and readily applied, and by using the pocket and extensible back moving within the same I overcome the objectionable features incident to a back connected to both sections, but made loose to allow for thickening the book contents--namely, the bulging or gaping of the back-section and incidental thereto the exposure of the inner construction. 80

What I claim as new, and desire to secure by Letters Patent, is—

1. In a binder for sheet-music, or the like, the combination of two separable cover-sections B and C, said section B comprising an inner sheet of cardboard t and an outer sheet of cardboard n , the sheet t being provided with a securing-strip D having the attaching-strips r' of linen pasted upon the inner and outer surfaces of the rear edge of the cardboard, and the sheet n being provided with sheets of flexible material n' and m on the outer and inner surfaces respectively, both prolonged to produce the flexible back E, and said section C being provided similarly with inner and outer sheets of cardboard separated at the rear edges to afford a pocket k , said inner sheet of the section C being further provided with a securing-strip D to coact with the like strip on the section B, substantially as and for the purpose set forth. 95

2. In a binder for sheet-music, or the like, the combination with two separable cover-sections, of securing-strips D, each comprising narrow parallel strips of cardboard s pasted close together upon a wider strip of linen r said strip of linen being folded to bring said strips of cardboard to a superimposed position and one of the strips D being provided with binding-posts q , each strip of linen being of sufficient width to afford, after folding, strips r' between which is pasted a sheet of the cover-section, substantially as described. 110

3. A binding-strip comprising a plurality of strips of paper, each provided with a gummed surface, said strips having their gummed surfaces turned toward each other, all being folded longitudinally, and a flexible securing-strip folded longitudinally and sewed on its line of folding to said strips of paper at their line of folding, substantially as described. 120

4. A binding-strip comprising a plurality of strips of paper, each provided with a gummed surface, said strips having their gummed surfaces turned toward each other, all being folded longitudinally, a strip of thick 130

paper h' covered with linen h^2 , a strip of cardboard h^3 cemented to one edge of the strip h' , linen stitches or the like securing the gummed strips of paper to the combined strip h', h^2 at the longitudinal center line, said strip being folded back at the line of sewing and cemented to the exposed surface of the cardboard strip h^3 and said composite securing-

strip being supplied with perforations as shown, substantially as and for the purpose to set forth.

HENRY E. VEIT.
